UNITED STATES PATENT OFFICE.

ALFRED L. STREETER, OF CHICAGO, ILLINOIS.

BRAKE-SHOE.

1,076,922.

Specification of Letters Patent.

Patented Oct. 28, 1913.

Application filed December 19, 1912. Serial No. 737,653.

To all whom it may concern:

Be it known that I, ALFRED L. STREETER, a citizen of the United States, and a resident of Chicago, in the county of Cook and State 5 of Illinois, have invented a certain new and useful Improvement in Brake-Shoes, of which the following is a specification.

This invention relates to brake shoes and relates particularly to brake shoes of the 10 type comprising back sections of a suitable, strong, tough metal, as malleable iron, provided with usual attaching and guide lugs for securing said back sections into the brake heads, and separate wearing sections adapted 15 to be detachably connected to said back sections, whereby, as said wearing sections are worn out, they may be removed and replaced by new wearing sections.

A primary object of my invention is to 20 provide improved means for securing the wearing sections of the shoes to the back sections thereof, whereby said wearing portions may be conveniently and quickly detached and replaced, which will be simple, 25 strong and durable, and which will operate to connect said wearing sections securely to said back sections.

A further object of my invention is to 30 provide a brake shoe of new and novel construction, the wearing surface of which comprises relatively hard and soft portions, the soft portions of said wearing section providing the desired traction or frictional engagement between the brake shoes and the 35 car wheels, and the hard sections thereof preventing excessive wear and greatly increasing the life of the shoe.

To effect the object of my invention as it 40 relates to improved means for securing the detachable and removable wearing sections thereof to the back sections, the invention consists of the various features and details of construction hereinafter described and claimed.

To effect the object of the invention as it 45 relates to providing a shoe, the wearing surface of which comprises relatively hard and soft portions, my improved brake shoe consists of a suitable body portion of usual 50 shape, formed in the face or wearing surface of which are transverse recesses or openings which terminate at short distances, say one-quarter of an inch from opposite sides of the brake shoe, said brake shoe being formed from white cast iron and being only 55 partly annealed, so as to convert the outer

portions of said brake shoe into soft, malleable iron, leaving the inner portions practically unchanged and very hard, said malleable iron and white cast iron merging into each other gradually, thus preventing the formation of sharp cutting edges in the faces of the shoes.

In the accompanying drawings, in which my invention is fully illustrated—Figure 1 is a back view of a brake shoe embodying my invention, showing the back section and wearing section thereof only partially engaged with each other, the attaching lug being shown in plan section to expose the means for securing the back and wearing sections of the shoe together; Fig. 2 is a central sectional view of my improved brake shoe, the back and wearing sections thereof being in full engagement with each other; Fig. 3 is a fragmentary sectional plan view of a modified construction, substantially similar to that portion of Fig. 1 which is shown in plan section; and Fig. 4 is a transverse sectional view on the line 4—4 of Fig. 3.

Referring now to Figs. 1 and 2 of the drawings, A designates, as a whole, a brake shoe embodying my invention, said shoe comprising a wearing section A' and a back section A², said back section A² being provided with a usual attaching lug a and guide lugs a', by means of which it is adapted to be secured in the brake head (not shown).

In accordance with my invention, the 90 wearing section A' is adapted to be connected to the back section A² in the following manner: Formed on the back of the wearing section A' is a stud 1, formed on which are lugs or projections 2. The stud 1 is adapted to be inserted through a hole or opening 3 which is formed through the center of the back section A², said opening 3 being provided with slots or lateral extensions 4 adapted to permit the passage there-through of the lugs or projections 2 on said stud 1, the relation being such that when the stud 1 and lugs or projections 2 thereon are inserted through the hole 3 and the lateral extensions 4 thereof, said lugs or projections 2 on said stud may be interlocked with the ledges formed by the upper surfaces of the parts 5 of the back section A intermediate the slots 4 by turning the wearing section A' and the back section A² relatively to each other to bring said wearing and back sections in line with each other.

The lugs 2 and slots 4 are preferably so arranged that to insert the lugs 2 through the slots or openings 4, it will be necessary to turn the wearing section A' and back section A² substantially at right angles to each other.

In order that the stud 1 and lugs or projections 2 thereon may not obstruct the key opening 6 in the attaching lug a, said stud 10 1 is made of such length that when said stud and the lugs or projections thereon are in full engagement with the back 1, the end of said stud will not project into said key opening, and a recess being formed in the 15 side of said key opening substantially equal in depth to the thickness of the lugs 2 on the stud 1. Also, in order that the lugs 2 may not interfere with turning of said sections A', A² relatively to each other, the 20 sides of the key opening 6 are cut away substantially concentric with the axis of the hole 3 to form openings of suitable size to receive said lugs or lateral projections 2, as shown at 8, Fig. 1.

25 In order to lock the ends of the wearing sections A' to the back section A², dovetailed tongues 9 are formed on the ends of said wearing sections A² which are adapted to engage corresponding dovetailed grooves 30 10 formed in the inner surface of the back section A² adjacent to its ends, both said dovetailed tongues and grooves being arranged concentric with the axis of the stud 1 on said wearing section 2 and of the hole 35 3 in the back section A², the relation being such that when the stud 1 is inserted through the hole 3 and the sections of the shoe are turned into line with each other, said tongues 9 will enter said grooves 10.

40 Pivotal movement of the sections of the shoe A relatively to each other in the direction to effect engagement of the tongues 9 with the grooves 10 is adapted to be limited by means of suitable stops, formed, as 45 shown, by closing the ends of said grooves opposite to the entrance ends thereof, as shown at 11, the relation being such that when the inner ends of the tongues 9 strike the closed ends 11 of the grooves 10, the 50 sections A' and A² of said shoe will be in line with each other. Preferably, also, means are provided for preventing accidental turning of the sections of said shoe relatively to each other after they have been 55 connected. As shown, said means consist of ribs 12 formed on the under sides of the lugs 2, which are adapted to engage grooves 13 formed on the ledges 5 on the back section A² when the sections of said shoe are 60 turned into full designed engagement with each other.

As a modification of the construction shown in Figs. 1 and 2, I contemplate making the lugs on the attaching stud on the 65 wearing section of the shoe in the form of

a head which is provided with a hole or opening, which, when the sections of the shoe are in full designed engagement with each other, will register with the key opening in the attaching lug formed on the back section of the shoe. With this construction, it is obvious that, when the shoe is inserted through the key opening in the attaching lug, it will also pass through the hole in the head on said attaching stud, thereby securing the wearing section of the shoe to the 70 brake head independently of the back section of the shoe, and also effectually locking the sections of said shoe against pivotal movement relatively to each other. This modification is shown in Figs. 3 and 4 of the drawings, referring to which A³ designates the wearing section of the shoe, A⁴ the back section thereof, a² the attaching lug formed on said back section, 1' the stud on the wearing section A³, 3' the hole or opening in the back adapted to receive said stud, 2' the lugs on said stud 1' adapted to engage with the ledges 5' on said back section A⁴, and 4' the slots in the sides of the 80 central hole or opening 3' adapted to permit the passage of the lugs 2'. In said modified construction, the lugs 2' are formed by the shoulders at the under side of a head 14 on the stud 1', which is substantially the same 85 in shape in horizontal section as the lugs 2. Formed through said head 14 is an opening 15 which is of the same size and shape as the key opening 6' in the attaching lug a², and which is adapted to register with said 90 key opening when the sections of said shoe are turned into full designed engagement with each other. In order to make the opening 15 through the head 14 of desired size, the dimensions of said head are necessarily 95 made larger than the corresponding dimensions of said hole or opening, the sides, top and bottom of the key opening 6' in the attaching lug a² being recessed to receive said head 14 and to provide for desired pivotal 100 movement thereof, as indicated at 16.

Again referring particularly to Figs. 1 and 2 of the drawings, the wearing portion of the shoe A, specifically the wearing section A', is made of white cast iron, the outer 115 surface of which to a depth of about one-eighth of an inch is converted into malleable iron by the usual process of annealing. Said shoes will thus consist of an outer shell of malleable iron, indicated by a³, which will 120 be soft and will provide the necessary traction or friction to render the braking action of the shoe effective, and an inner portion of unconverted white cast iron, indicated at a⁴, which is very hard and will enable the 125 shoe to resist wear. Also, the malleable and white cast iron portions of the shoe will merge into each other gradually, thus effectually preventing the formation of sharp cutting edges in the face of the brake shoe, 130

which would quickly cut and wear the tires of the car wheels to which they are applied. In order to increase the malleable area of the face of the brake shoe as compared with the white cast iron area, holes 17 are formed transversely in the face of the shoe, the number of said holes being increased or decreased as it is desired to increase or decrease the relative areas of malleable and of white cast iron. Preferably, also, said holes 17 extend to within a short distance, say one quarter of an inch of the side of the brake shoe. At these points, the lateral wall of the brake shoe will be converted into malleable iron entirely through, thus rendering it strong and tough and greatly reducing the chances of its breaking in use.

I claim:—

1. As a new article of manufacture, a brake shoe comprising separate back and wearing sections and means for detachably connecting said sections, said means comprising a stud on said wearing section, projections thereon, a hole formed in said back section to receive said stud and the projections thereon, ledges within said hole adapted for engagement by the projections on said stud, and interlocking parts on said back and wearing sections constructed and arranged for engagement and disengagement by turning said back and wearing sections relatively to each other, substantially as described.

2. As a new article of manufacture, a brake shoe comprising separate back and wearings sections and means for detachably connecting said sections, said means comprising a stud on said wearing section, projections thereon, a hole formed in said back section to receive said stud and the projections thereon, ledges within said hole adapted for engagement by the projections on said stud, and interlocking tongues and grooves on said sections constructed and arranged for engagement and disengagement by turning said sections relatively to each other, substantially as described.

3. As a new article of manufacture, a brake shoe comprising separate back and wearing sections and means for detachably connecting said sections, said means comprising a stud on said wearing section, a head thereon provided with shoulders at its under side, a hole formed in said back section adapted to receive said stud and the

head thereon, ledges within said hole adapted for engagement by the shoulders on said head, and interlocking parts at the ends of said back and wearing sections constructed and arranged for engagement and disengagement by turning said back and wearing sections relatively to each other, said head being provided with a key opening which is adapted to register with the key opening of the shoe when said sections are turned into line with each other, substantially as described.

4. As a new article of manufacture, a brake shoe comprising separate back and wearing sections and means for detachably connecting said sections, said means comprising a stud on said wearing sections, projections thereon, a hole formed in said back section adapted to receive said stud and the projections thereon, ledges within said hole adapted for engagement by the projections on said stud, interlocking parts on said back and wearing sections constructed and arranged for engagement and disengagement by turning said back and wearing sections relatively to each other, and stops adapted for defining full engagement of said interlocking parts, substantially as described.

5. As a new article of manufacture, a brake shoe comprising separate back and wearing sections and means for detachably connecting said sections, said means comprising a stud on said wearing sections, projections thereon, a hole formed in said back section adapted to receive said stud and the projections thereon, ledges within said hole adapted for engagement by the projections on said stud, and interlocking tongues and grooves on said back and wearing sections constructed and arranged for engagement and disengagement by turning said back and wearing sections relatively to each other, corresponding ends of said grooves being closed to form stops which define full engagement of said interlocking tongues and grooves with each other, substantially as described.

In testimony that I claim the foregoing as my invention, I affix my signature in presence of two subscribing witnesses this 10th day of December, A. D., 1912.

ALFRED L. STREETER.
